[57] CLAIM

The ornamental design for a paint roller handle, as shown and described.

DESCRIPTION

FIG. 1 is a side elevational view of a paint roller handle showing my new design with the handle shown broken away to indicate indeterminate length and the other sides being the same in appearance as the side shown; FIG. 2 is a front perspective view thereof; FIG. 3 is a front elevational view thereof; and, FIG. 4 is a rear elevational view thereof.

The broken line showing of a paint roller rod in FIG. 2 is for illustrative purposes only and forms no part of the claimed design.
